GOTTFRIED BERNHARD MÜNCH, OF LEIPZIG, GERMANY, ASSIGNOR TO ALLVOR-APPARTE-GESELLSCHAFT MIT BESCHRÄNKTER HAFTUNG, OF WURZEN, GERMANY.

MECHANISM FOR OPENING AND CLOSING SLIDING WINDOWS.

1,137,076.

Specification of Letters Patent. Patented Apr. 27, 1915.

Application filed August 8, 1913. Serial No. 783,716.

To all whom it may concern:

Be it known that I, GOTTFRIED BERNHARD MÜNCH, a citizen of the German Empire, residing at Leipzig, in Germany, have invented certain new and useful Improvements in Mechanism for Opening and Closing Sliding Windows, of which the following is a specification.

The object of this invention is to effect certain improvements in mechanism for opening and closing sliding windows and retaining same in selected positions intermediate of the fully closed and fully open positions.

15 The improved mechanism may be applied to the windows of railway carriages and other vehicles, but the invention is not restricted to carriage windows.

20 The invention is illustrated in the accompanying drawings, in which,

Figures 1 and 2 show an embodiment of the same, Fig. 1 being a vertical cross section, and Fig. 2 a front elevation, partly in section.

25 In the construction shown the rotatable handle for raising and lowering the window comprises a part a^2 fixed across a cup-shaped member a^3 , the latter being fixed to a spindle b^2 connected to suitable gearing G for 30 moving the window. The spindle b^2 has bearing in a housing m^2 which partly encloses the cup a^2 . A cover r^2 is pivoted at t^2 to the housing and normally lies in front of same, covering the handle. The cover r^2 35 has a tooth u , and the cup a^2 has at its rim a ring of teeth u^1 , with which the tooth u can be engaged, with the handle in any angular position, to lock the handle and prevent movement of the window.

40 Formed on the cover, near the pivot t^2 , is a cam t^3 , and the flange of the housing m^2 has a hole near this cam, in which there is an axially slideable rod q . This rod abuts against a double-armed lever p^4 which is 45 pivoted at p^3 and carries at its upper end a cross-bar p^2 . A spring p^5 acting on the lever

p^4 normally thrusts the bar p^2 against the window, and thus prevents rattling of the latter. The spring also thrusts the lower arm of the lever against the rod q whereby 50 the latter is pressed against the cam t^3 .

By raising the cover r^2 the tooth u is disengaged from the ring of teeth u^1 on the member a^3 , so that the handle can be turned, for raising or lowering the window. The 55 raising of the cover r^2 also causes the cam t^3 to push the rod q and rock the lever p^4 so that the bar p^2 is removed from contact with the window. When the window has been moved to the desired position, the cover 60 is lowered again, and locks the handle, with the gear connected thereto, and the cam t^3 allows the spring p^5 to thrust the bar p^2 against the window again.

It will be noted that while the handle is 65 unlocked that circumstance is rendered conspicuous by the fact of the cover being raised, so that there is but slight risk of the handle being left unlocked through negligence.

70 What I claim as my invention and desire to secure by Letters Patent of the United States is:—

In mechanism for raising and lowering a sliding window, the combination of a fixed 75 housing, a rotatable actuating handle in said housing, having a ring of teeth, a hinged cover on said housing having a tooth adapted to engage said ring of teeth, for locking the handle, a movable device adapted to automatically bear against the window, to prevent rattling thereof, and means whereby the opening of said cover removes said movable device from contact with the window. 80

85 In witness whereof I have signed this specification in the presence of two witnesses.

GOTTFRIED BERNHARD MÜNCH.

Witnesses:

RICHARD CLAUS,
RUDOLPH FRICKE.
